Altissimo

UNITED STATES PATENT OFFICE.

EUGENE J. BUCHHEIM, OF HIGHLAND, ILLINOIS.

ORGAN.

Application filed September 25, 1924. Serial No. 739,836.

My invention relates to that part of an organ by which the great registers thereof may be coupled and uncoupled with the pedal keyboard, at will, under the control of the operator, this control being commonly effected through the medium of a foot-operated element, and the mechanism controlled by this element being such that the coupling and uncoupling referred to is effected alternately by actuation of the foot-operated element always in the same direction.

One of my objects is to provide a novel and positively-operating mechanism by which the coupling and uncoupling of the great registers of the organ with the pedal keyboard may be effected under electric control. Another object is to provide for this control by means which are wholly electrically controlled; and other objects as will be manifest from the following description:

Referring to the accompanying drawings:

Figure 1 is a view in side elevation of organ-mechanism embodying my invention, the mechanism having associated therewith a manually-operated stop-key shown as projecting through the keyboard illustrated in section. Figure 2 is a view, partly diagrammatic, showing the mechanism illustrated in Fig. 1 but viewing it from the opposite side thereof. Figure 3 is a view in sectional elevation of a foot-operated element in connection with which my invention may be used and through the medium of which the great registers may be coupled to and uncoupled from, the pedal key-board; and Figure 4, a view, in the nature of a diagram, showing the various circuit connections between the several parts of the mechanism shown in Figs. 1 and 2 and between this mechanism and the foot-operated element of Fig. 3.

I have chosen to illustrate my invention in a structure operated wholly by electrical means, for controlling the opening and closing of the circuit through the medium of which the coupling of the great registers with the pedal keyboard, is effected, though without intending to limit the invention, as to certain features thereof to a structure wholly electrically-operated. The mechanism shown comprises a bracket 10 shown as rigidly secured, as by the screws 11, to the rear side of the keyboard 12 which is provided with an opening 13 for a stop-key 14, in the form of a tablet. Mounted on a

rearwardly extending arm 15 of the bracket 10, is a switch device comprising six contact members 16 to 21 inclusive, each preferably of spring metal and each secured between its ends to the arm 15, with interposed insulation 22. The contacts 16 and 18 are shown as provided with down-turned ends 16^a and 18^a, respectively, and the contact 21 with an up-turned end 21^a, there being interposed between the contacts 17 and 18, a strip 23 of insulating material. The contacts 18 and 19 in the particular construction shown and which are adapted to directly cooperate with each other, are the ones which, in practice, would be interposed in the circuit in which the electrical mechanism for controlling the coupling and uncoupling of the great registers with the pedal key board, is interposed, the closing of the circuit by engaging the contact 19 with the contact 18 operating to effect the coupling referred to and the disengaging of these contacts effecting the uncoupling action.

The electrical mechanism just referred to as controlled by the contacts 18 and 19 may be of any suitable construction, as for example that shown and described in the application for U. S. Letters Patent of Louis J. Wick, Serial No. 717,090, filed May 31, 1924, the electro-magnet contacting device of which would be connected with the contacts 18 and 19 and the sets of contacts of which would connect, respectively, with the several sound-producing devices of the great registers and the pedal keys separately controlling the sound-producing devices of the great registers.

The contacts 16 and 17, and the contacts 20 and 21, cooperate, respectively, with each other and are provided for controlling electrically-operated mechanisms hereinafter described, for actuating in opposite directions, alternately, mechanism also hereinafter described, for conditioning the contacts 18 and 19 relative to each other.

The various contacts 16 and 21 inclusive, are adapted for simultaneous conditioning by a single operating member which, in the construction shown, is an armature 24 pivotally connected at its forward end, as indicated at 25, with the bracket 10, this armature, in the particular construction shown, rigidly carrying the stop-key 14, whereby this armature and stop-key are in effect a unitary structure. The armature

24 is provided with a laterally extending plate 26 of insulating material which extends between the contacts 19 and 20 and through the medium of which, in the oscillations of the armature 24, the conditioning of the members of these various sets of contact devices, is effected. It may be here stated that the parts described are so proportioned and arranged that when the armature 24 is in the position shown in the drawings, the contact members 16 and 17 and the contact members 18 and 19 are out of respective engagement and the contact members 20 and 21 are in engagement, as shown in Fig. 2, and when the armature 24 is rocked upwardly, as by the means hereinafter described, the contact members 16 and 17 and 18 and 19 are caused to be in engagement with each other, respectively, and the contacts 20 and 21 out of engagement with each other. Thus the contact devices formed of the members 16 and 17 and 18 and 19, respectively, are open in the normal position of the structure and the contact device formed of the members 20 and 21 is closed.

The armature 24 is provided at its rear end with oppositely extending arc-shaped extensions 27 and 28, the arcs of which are described about the pivot 25, these extensions co-operating, respectively, with the cores 29 and 30 of electro-magnets 31 and 32 rigidly secured at their cores to, and extending rearwardly from, the bracket 10, these magnets being shown as located one above the other in spaced relation with the armature 24 interposed therebetween. The faces of the cores 29 and 30 which are opposed by the arc-shaped extensions of the armature 24 are preferably of arc-shape described about the pivot 25 as a center whereby these extensions are spaced from the ends of the cores a uniform distance at all times.

The magnets 31 and 32 which are separately energizable in alternation, operate to oscillate the armature 24, the magnet 31, upon being energized, assuming the parts of the structure to be in the position shown in the drawings, operating to rock the armature 24 upwardly to a position in which the contact device formed of the contacts 20 and 21 is opened, and the magnet 32 operating, when energized, following the de-energizing of the magnet 31, operating to restore the various parts to the position shown in the drawings.

The mechanism shown is designed to be operated, to effect the oscillating of the armature 24, by alternately energizing the electro-magnets 31 and 32, where the controlling device is of such character that it is operable in the same direction for both the coupling and uncoupling movements, as for example, the "great-to-pedal" foot-operated element hereinbefore referred to,

as commonly provided in organs. In Fig. 3, a construction of the foot-operated element of the general construction above referred to is shown, this element being formed with the base portion 33 carrying spring contact fingers 34 insulated from each other and normally spaced apart, the free ends of these fingers extending into the path of movement of a current-conducting, bridging, head 35 carried on the inner end of a plunger 36, reciprocable in the base 33, a coil spring 37 operating to automatically return the plunger 36 to the position shown in Figs. 3 and 4, following the depressing of the plunger. The mechanism shown is of such character that each time the plunger 36 is depressed to bridge the contacts 34, one or the other of the magnets 31 or 32 is energized, these magnets being energized alternately through the switch device of Fig. 3. Referring now to the mechanism for accomplishing the operation just stated, this mechanism comprises a plurality of electro-magnets 38 and 39, having cores 40 and 41 at which these magnets are supported on brackets 42 and 43 carried by the arm 15 and insulated therefrom. The magnets 38 and 39 are provided with armatures 44 and 45 pivotally supported at their upper ends, as indicated at 46 and 47, respectively, on the brackets 42 and 43, the outer extremities of these armatures terminating in the arc-shaped extensions 48 and 49 which directly cooperate with the cores 40 and 41, springs 50 and 51 interposed between the armatures 44 and 45 and the magnets 38 and 39, respectively, yieldingly holding these armatures in the normal position represented in the drawings. Cooperating with the magnet 38 and the armature 44 is a switch device 52 shown as formed of three springs metal contact strips 53, 54 and 55, secured to an arm 56 of the bracket 42 and insulated from each other by the insulation 57. The extremities of the strips 53 and 55 terminate in the portions 58 and 59 which extend toward each other and oppose the opposite faces of the contact strip 54, but are spaced apart a distance greater than the thickness of the contact 54. These contact members are so constructed and arranged that in the normal position of the parts the contact 54 engages the contact 55, but is adapted to be flexed out of engagement with the contact 55 and into engagement with the contact 53. The shifting of the contact member 54, as stated, is effected through the medium of an extension 60 provided on the armature 44 and into the path of movement of which, upon becoming actuated by energizing the magnet 38, the contact member 54 extends.

The magnet 39 and armature 45 cooperate with switch mechanism represented generally at 61 of the same construction and op-

erable in the same manner as explained of the switch 52, the portions of the switch mechanism 61 corresponding with the parts 53 to 60 inclusive, being represented at 62 to 69 inclusive, respectively.

- The various electrical connections between the parts of the switch mechanism shown in Figs. 1 and 2, is illustrated by the diagrammatic showing in Fig. 4 and comprises the following: The contact 16 is connected by a wire 70 with the contact 64; the contact 17 connects, by a wire 71, with one of the terminals of the electro-magnet 38, the other terminal of which connects with a wire 72 which is connected with the terminals 31^a and 32^a of the magnets 31 and 32. The other terminals of these two magnets, represented at 31^b and 32^b, are connected with the contacts 62 and 53, respectively, by the wires 73 and 74, the wire 74 being connected, by a wire 74^a, with the wire 71 and the wire 73 being connected, by a wire 75, with one of the terminals of the magnet 39, the other terminal of which connects by a wire 76 with the wire 72; the contact 21 connects, by a wire 77, with the wire 73; the contact 20 connects, by a wire 78, with the contact 55; and the contacts 54 and 63 are connected together by a wire 79.
- In the particular arrangement shown in Fig. 4, the source of current controlled by the mechanism shown, is a generator represented at 80, one terminal of this generator being connected by a wire 81 with the terminal 31^a of the magnet 31, and the other terminal of this generator being connected, by a wire 82, with one of the contacts 34 of the switch device, shown in Fig. 3, the other contact 34 of this switch device being connected by a wire 83, with the wire 79. The parts of the mechanism shown are represented in the drawings as in normal position, in which the stop-key 14 is elevated, and the contact strips 18 and 19 are out of engagement with each other whereby the circuit in which the mechanism (not shown) for controlling the coupling of the great registers with the pedal keyboard, is open and this mechanism is in uncoupled condition. In this position of the parts, the contacts 54, 63, and 20 are in engagement, respectively, with the contacts 55, 64, and 21, the contacts 16 and 18 being out of engagement with the respective contacts 17 and 19. The depressing of the plunger 36 to a position in which the contacts 34 are bridged, causes the circuit in which the magnet 31 is interposed to become energized with the result of raising the armature 24 to a position in which the contacts 17 and 19 are caused to engage with the contacts 16 and 18, respectively, and the contact 20 to disengage from the contact 21, thereby closing the circuit through the mechanism, hereinbefore referred to, for actuating the coupler

to a position in which the great registers of the organ would be connected for operation by the keys of the pedal keyboard. The circuits established by actuating the switch plunger 36, as stated, are as follows, from the generator 80 through wire 82, switch device of which the contacts 34 are parts, wire 83, wire 79, contact 54, contact 55, wire 78, contact 20, contact 21, wire 77, magnet 39, wire 76, wire 72 and wire 81, back to generator 70. The coil 39 thus becomes energized 75 and swings the armature 45 to the left in Fig. 4, thereby disengaging the contact 63 from the contact 64 and engaging the contact 63 with the contact 62, whereupon the following described circuit is created; from the generator 80, wire 82, and switch device, wire 83, wire 79, contact 63, contact 62, wire 73 to contact 31^b, thence through the upper magnet 31 to wire 81 back to generator 80. Thus energizing the magnet 31 rocks the armature 24 in clockwise direction in Figs. 2 and 4, with the result of raising the plate 26 and forcing the contact 19 into engagement with the contact 18 and the contact 17 into 85 engagement with the contact 16, and permitting the contacts 20 and 21 to separate. The engaging of the contact 19 with the contact 18, as stated, operates to close the circuit through the mechanism, hereinbefore referred to, for effecting the coupling of the great registers with the pedal keyboard, the armature 24 remaining in the position to which it is actuated, as stated, after the operator discontinues pressure on the plunger 36, by virtue of the spring device 84 secured at its forward end to the bracket 10, as represented at 85, with its rear end deflected as represented at 86, between which deflected end, and a bar 87 on the armature 24, a rod 88 is confined under the tension of this spring, the rod 88 extending below a line connecting the pivot 25 and the point at which the rear end of the rod engages the spring part 86, in the normal position 100 of the armature (Figure 1) and extending above this line when the armature is raised by the energizing of the magnet 31. When the operator again depresses the plunger 36, to return the armature 24 to 115 normal position (Figs. 1 and 2), the following circuit is established. From the generator 80, through wire 82, switch device of which the contacts 34 are parts, wire 83, wire 79, contact 63, contact 64, wire 70, contact 16, contact 17, wire 71, magnet 38, wire 72 and wire 81 back to generator 80. Thus energizing the magnet 38 causes the armature 44 to swing to the left in Figs. 2 and 4, thereby disengaging the contact 54 from the contact 55 and moving the contact 54 into engagement with the contact 53, whereupon the following circuit is established. From generator 80 through wire 82, switch device, wire 83, wire 79, contacts 54 and 53, 120 130

wire 74, terminal 32^b, magnet 32, terminal 32^a, wire 72 and wire 81 back to generator. Thus energizing magnet 32 operates to rotate the armature 24 in counterclockwise direction in Figs. 2 and 4 back to the normal position therein shown, with the result that the contacts 18 and 19 disengage and uncoupling action between the great registers and the pedal keyboard, occurs. The foregoing description of the operation of the structure, describes one complete cycle of operations involving the coupling and uncoupling of the great registers to the pedal keyboard, it being understood that in the succeeding operations of the plunger 36, by the operator, this cycle of operations is repeated.

It will be noted that, if desired, a plurality of the switch devices such as, or corresponding to, the switch of Fig. 3 may be employed and located at different places on the instrument and through the medium of any one of which the mechanism described may be operated, in which case the switches referred to may be arranged, in parallel, in the generator circuit.

While the element 36 is described as a foot-operated element it will be understood that such element may be provided of a construction and so positioned as to be accessible for hand-control, if desired. Furthermore, if desired, a plurality of elements corresponding with element 36, all foot controlled, or all hand controlled, or some foot controlled and the others hand controlled, may be provided, these elements being located at different positions on the instrument as desired, and through any one of which the control of the electrical relay mechanism described may be effected.

While I have illustrated and described a particular construction embodying my invention, I do not wish to be understood as intending to limit it thereto, as the same may be variously modified and altered, and the invention embodied in other forms of structure, without departing from the spirit of my invention.

What I claim as new, and desire to secure by Letters Patent, is:

1. The combination with mechanism to be controlled, of controlling mechanism therefor, comprising a controlling element operable, in each operation, in the same direction, and electrical mechanism interposed between said first-named mechanism and said controlling element and operating, upon successive operations, respectively, of said controlling element, to effect different conditionings, respectively, of said first-named mechanism.

2. In a musical instrument, the combination with the great registers and pedal keyboard thereof, of coupling mechanism controllable to effect the coupling and un-

coupling of said great registers with said pedal keyboard, a controlling element operable, in each operation, in the same direction, and electrical mechanism interposed between said coupling mechanism and said controllable element and operating upon one actuation of said controlling element to cause said coupling mechanism to be in coupled condition and upon the next succeeding operation of said element to be in uncoupled condition.

3. The combination with mechanism to be controlled, of controlling mechanism therefor, comprising a controlling element operable, in each operation, in the same direction, and electrical mechanism interposed between said first-named mechanism and said controlling element and comprising an armature by the movements of which said first-named mechanism is controlled, a plurality of magnets with which said armature co-operates and by the alternate energizations of which said armature is moved in opposite directions, and mechanism operable to alternately energize said magnets in successive actuations of said controlling element.

4. In a musical instrument, the combination with the great registers and pedal keyboard thereof, of coupling mechanism controllable to effect the coupling and uncoupling of said great registers with said pedal keyboard, a controlling element operable, in each operation, in the same direction, and electrical mechanism interposed between said coupling mechanism and said controlling element and comprising an armature by the movements of which said coupling mechanism is controlled, a plurality of magnets with which said armature co-operates and by the alternate energizations of which said armature is moved in opposite directions, and mechanism operable to alternately energize said magnets in successive actuations of said controlling element.

5. The combination with mechanism to be controlled, of controlling mechanism therefor, comprising a controlling element operable, in each operation, in the same direction, and mechanism interposed between said first-named mechanism and said controlling element operating upon successive operations, respectively, of said controlling element to effect different conditioning, respectively, of said first-named mechanism comprising relays having contact devices, mechanism controlled by said relays, a movable member controlled by said last-named mechanism, contacts controlled by said movable member, and circuit connections between said contact devices and said contacts, the whole being so constructed and arranged that when said movable member is in one position and said controlling element is operated, one of said relays will be actuated

to effect a certain conditioning of said first-named mechanism, and when said movable member is in another position and said controlling element is again actuated, the other of said relays will be actuated to effect a different conditioning of said first-named mechanism.

6. In a musical instrument, the combination with the great registers and pedal keyboard thereof, of coupling mechanism controllable to effect the coupling and uncoupling of said great registers with said pedal keyboard, a controlling element operable, in each operation, in the same direction, mechanism interposed between said coupling mechanism and said controlling element operating upon successive operations, respectively, of said controlling element, to cause said coupling mechanism to be in coupled and uncoupled condition, respectively, comprising relays having contact devices, mechanism controlled by said relays, a movable member controlled by said last-named mechanism, contacts controlled by said movable member, and circuit connections between said contact devices and said contacts, the whole being so constructed and arranged that when said movable member is in one position and said controlling element is operated, one of said relays will be actuated to cause said coupling mechanism to be in coupled condition, and when said movable member is in another position and said controlling element is again actuated, the other of said relays will be actuated to effect the uncoupling of said first-named mechanism.

7. The combination with mechanism to be controlled, of controlling mechanism therefor, comprising a controlling element operable, in each operation, in the same direction, and mechanism interposed between said first-named mechanism and said controlling element operating upon successive operations, respectively, of said controlling element to effect different conditioning, respectively, of said first-named mechanism comprising relays having contact devices, electrically operated mechanism controlled by said relays, a movable member controlled by said last-named mechanism, contacts controlled by said movable member, and circuit connections between said contact devices and said contacts, the whole being so constructed and arranged that when said movable member is in one position and said controlling member is operated, one of said relays will be actuated to effect a certain conditioning of said first-named mechanism, and when said movable member is in another position and said controlling member is again actuated, the other of said relays will be actuated to effect a different conditioning of said first-named mechanism.

8. In a musical instrument, the combination with the great registers and pedal key-

board thereof, of coupling mechanism controllable to effect the coupling and uncoupling of said great registers with said pedal keyboard, a controlling element operable, in each operation, in the same direction, mechanism interposed between said coupling mechanism and said controlling element operating upon successive operations, respectively, of said controlling element, to cause said coupling mechanism to be in coupled and uncoupled condition, respectively, comprising relays having contact devices, electrical mechanism controlled by said relays, a movable member controlled by said last-named mechanism, contacts controlled by said movable member, and circuit connections between said contact devices and said contacts, the whole being so constructed and arranged that when said movable member is in one position and said controlling element is operated, one of said relays will be actuated to cause said coupling mechanism to be in coupled condition, and when said movable member is in another position and said controlling element is again actuated, the other of said relays will be actuated to effect the uncoupling of said first-named mechanism.

9. In a musical instrument, the combination with the great registers and pedal keyboard thereof, of coupling mechanism controllable to effect the coupling and uncoupling of said great registers with said pedal keyboard, a controlling element operable, in each operation, in the same direction, mechanism interposed between said coupling mechanism and said controlling element operating upon successive operations, respectively, of said controlling element, to cause said coupling mechanism to be in coupled and uncoupled condition, respectively, comprising relays having contact devices, electric magnets controlled by said relays, an armature the position of which is controlled by said electric magnets, and contacts controlled by said armature, the whole being so constructed and arranged that when said armature is in one position and said controlling element is actuated, one of said relays will be actuated to cause said coupling mechanism to be in coupled condition and when said armature is in another position and said controlling element is again actuated, the other of said relays will be actuated to effect uncoupling of said first named mechanism.

10. In a musical instrument, the combination with the great registers and pedal keyboard thereof, of electrical mechanism for operating the sound-producing devices of the great registers upon actuating the keys of the pedal key board, and electrical mechanism for controlling the conditioning of said first-named electrical mechanism for operation and involving a controlling element operable, in each operation, in the same

direction, and operating upon successive operations to effect different conditionings of said last-named mechanism.

11. In a musical instrument, the combination with the great registers and pedal key-board thereof, of mechanism for operating the sound-producing devices of the great registers upon actuating the keys of the pedal key-board, and an electrical device 10 controlling the conditioning of said mechanism for operation, and electrical mechanism for controlling the condition of said electrical device to control the operation of said electrical device, and involving a controlling element operable, in each operation, in the same direction and operating upon successive operations to effect a different conditioning of said last-named mechanism.

12. In a musical instrument, the combination with the great registers and pedal key-board thereof, of mechanism for operating the sound-producing devices of the great registers upon actuating the keys of the 20

pedal key-board, a controlling element operable, in each operation, in the same direction, and means, operable wholly by electric current, and controlled by said controlling element, for controlling said mechanism. 25

13. The combination with mechanism to be controlled, of controlling mechanism therefor, comprising a controlling element operable, in each operation, in the same direction, and electrical mechanism interposed between said first-named mechanism and said controlling element and comprising 30 a movable member by the movements of which said first-named mechanism is controlled, a plurality of energizable members with which said movable member cooperates and by the alternate energizations of which 35 said movable member is moved in opposite directions, and mechanism operable to energize said energizable members in successive actuations of said controlling element. 40

EUGENE J. BUCHHEIM.
